VACUUM CUP HOLDER FOR TOWELS AND
THE LIKE

Albert J. Ganz, Los Angeles, Calif.

Application September 2, 1948, Serial No. 47,430

3 Claims. (Cl. 248—206)

1

The present invention relates to holders for towels and the like, particularly one employing a suction cup for application to a wall, and the primary object of the invention is to provide a device of this kind which is convenient to use, extremely simple and inexpensive to manufacture, and easily affixed to a wall for support. In this same connection, one of the features of the invention is the provision of an improved holder formed of two interfitting molded rubber parts, one of which constitutes the suction cup, and the other part being the towel-holding element; said parts being so shaped and arranged relative to one another that neither interferes with the proper functioning of the other, and both being likewise so shaped as to be readily produced by conventional molding processes.

A further object of the invention is to provide a holder embodying a novel towel-gripping member which is extremely simple, yet highly effective. This towel-gripping member is preferably formed in the shape of a flat-bottomed cup that is attached to the back of the suction cup with its bottom end presented outwardly. The exposed bottom end of the cup has a zigzag slit formed therein which extends from one side to the other, and when the sides of the cup adjacent the ends of the slit are pressed together, the edges of the slit are caused to spread apart and open outwardly so that the edge of a towel or other article can be inserted into the gaping slit. Upon being released, the cup returns to its normal shape, closing the slit and engaging the towel therein with a resiliency grip.

Another object of the invention is to provide a holder of the type described having a suction cup member that is particularly designed to give an enhanced sealing and gripping action. To this end, the periphery of the suction cup is given a special shape providing a second and separate vacuum sealing area around the outside of the primary suction area of the cup.

A still further feature of the invention is the provision of a suction cup towel holder of the class described, wherein the suction cup has a preformed hole at its center extending almost, but not entirely, through the cup from the back or outside surface thereof, so that a thumb tack can easily be pushed through the remaining material to mount the holder on a rough or porous surface of a type unsuited to the use of the suction cup in the usual manner.

The foregoing and other objects and advantages of the invention will become apparent to those skilled in the art upon consideration of the following detailed description of the preferred

2

embodiment thereof, reference being had to the drawings, in which:

Figure 1 is a perspective view of a holder embodying the principles of the invention;

5 Figure 2 is another view of the same, showing the manner in which the edges of the slit spread apart and gape outwardly when the gripping member is squeezed together adjacent the ends of the slit;

10 Figure 3 is an enlarged vertical section through the holder;

Figure 4 is an end view of a gripping member, showing another form of the zigzag slit;

15 Figure 5 shows still another form of the zigzag slit in the end of the gripping member;

Figure 6 is a sectional view through the holder applied to a smooth surface;

20 Figure 7 is a fragmentary sectional view showing the manner in which the suction cup member can be attached to a rough or porous surface by merely pushing the point of a thumb tack through the material at the bottom end of the preformed hole in the center of the suction cup;

Figure 8 is a perspective view illustrating the manner of assembling the device; and

25 Figure 9 is a perspective view illustrating the insertion of an article into the device.

In the drawings, the holder is designated in its entirety by the reference numeral 10, and comprises a suction cup member 11, and a gripping member 12. Both of these members are molded of either natural or synthetic rubber, and are provided with interfitting portions whereby the gripping member may be securely mounted on the back of the suction cup member for support.

30 The suction cup member 11 is circular in plan-form, and has a main generally frusto-conical wall, including sloping sides 14 and top 15, which may be of substantially uniform thickness, excepting for a special formation at the outer periphery.

35 Formed integrally with the side wall 14 and projecting outwardly from the back face 14a thereof is an annular mounting flange 13 which is preferably somewhat less in thickness than the thickness of the suction cup member at the point of their junction. Somewhat roughly speaking, the flange 13 preferably has a diameter of about 80% or a little less than the outside diameter of the entire cup. An inwardly directed lip 16 is 40 provided around the edge of the flange 13. The gripping member 12 is generally cup-shaped, with cylindrical side walls 20 and a flat, relatively thin outer end wall 21. Formed around the edge of the side walls 20 at the open end of the gripping member is an outwardly directed lip 22 which is

shaped to fit snugly within the groove formed by the mounting flange 13, lip 16, and outer face 14 of the suction cup member.

Figure 8 shows how the gripping member 12 is formed for ready and convenient assembly with the suction cup member 11. The member 12 is folded and pinched between the thumb and fingers, and while so held, is moved inside the wall or flange 13 of member 11, the lip 22 being placed inside the annular groove formed by the flange 16. The member 12 is then allowed to expand and its lip 22 is worked under the flange 16 all around. Clearly, by reason of the fact that the holder member 12 is open at its end corresponding to lip 16, it is susceptible of collapse, as to the position of Figure 8, and is hence capable of ready assembly and disassembly with respect to the gripping member 11.

The outer end wall 21 of the gripping member 12 is formed with a towel-receiving slit—preferably a zigzag slit 23 extending substantially from one side of the member to the other. One form of the zigzag slit 23 is shown in Figure 1, while another form is shown at 23a in Figure 4, and still a third form is shown at 23b in Figure 5. The chief characteristic of each of these slits is that it is generally zigzag in configuration, affording a long line of slit, as well as gripping teeth and this slit extends in a generally diametral direction across the circular end wall 21 substantially from one side to the other. It will be observed that the zigzag slit 23b in Figure 5 is curvate, each of the points of reversal in direction being smoothly curved. The feature that makes these zigzag slits more effective than the usual three-way or four-way radiating slits that have heretofore been employed is the fact that when the gripping member is squeezed from opposite sides adjacent the ends of the slit, the edges of the slit gape open and point outwardly, as shown in Figure 2, making it possible to insert the edge or a corner of a towel or similar object between the toothed edges of the slit. The resilient gripping member 12 is then released and springs back to its original form, closing the edges of the slits together on the article inserted therein and engaging the same in a yieldable grip. The article is removed from the gripping member by merely giving it a slight tug, which pulls it free of the resilient grip. Alternatively, the corner of a towel or the like, such as T in Figure 9, can simply be forced in between the gripping points of the holder by a thrust of the index finger. In such action, the flexible holder 12 readily expands or deforms with any stretching forces so imposed, and there is no tendency to tear the slit at its ends or corners.

The side wall portion 14, formed preferably at about 20° to a transverse plane, has an outside surface 14b, outside flange 13, which slopes at increased abruptness (for example, at about 40° with the transverse plane) toward the peripheral edge of the cup, and the latter preferably has a slightly raised bead 14b. The inside surface 14c of side wall 14 converges toward outside surface 14b to a minimum wall thickness point 14d, and from there has a surface 14e which slopes to the periphery of the cup at an increased inclination—say at about 45° to the transverse plane. The cup is thus given a minimum thickness section near but somewhat spaced inside its periphery, outside of which is a flap portion 24 of the shape described, and there is an obtuse angle of about 155° between the inner wall surface 14c and the flap surface 14e.

The usual method of mounting the holder 10 on a wall or other surface is to moisten the suction face of the vacuum cup 11, and then press the same firmly against a smooth surface. Air is expelled from underneath the suction cup, and atmospheric pressure thereafter holds the cup firmly against the wall surface. As the cup is applied to the wall surface, the main side wall 14 thereof bends relative to top 15 to flatten toward the wall surface, and the flap portion 24 bends outwardly likewise, but through a few additional degrees of angle because of its initial angular relationship to wall 13. The resilient tendency for the flap portion to return to its initial angle relative to wall 14 causes its periphery to contract slightly, which forces the cup wall upwardly a short distance in the region of the thin section 14d, as has been indicated in Figure 6 at 25. The result is that there is a double vacuum seal, first, the sealing area 26 inward of the annular slightly raised cup region 25, and second, an additional annular sealing area all outside the outside of the region 25. In full effect, there are actually two vacuum cups, one outside the other; or in another manner of speaking, there is the usual vacuum cup, surrounded by an annulus having a resiliently raised median section creating an additional vacuum adhesion means. The result is a novel and improved vacuum cup having especially effective vacuum adhesion properties.

If the wall surface is rough or porous, the suction cup will not adhere to it, and it is necessary then to mount the member 11 on the wall, using a thumb tack or similar fastening member. Accordingly, a hole 27 is formed in the center of the suction cup member, said hole extending almost but not entirely through the member so that a thumb tack 28 can easily be pushed through the remaining material and into the wall, as shown in Figure 7.

While I have shown and described in considerable detail what I believe to be the preferred form of my invention, it is to be understood that such details are not restrictive, and that various changes may be made in the shape and arrangement of the several parts without departing from the scope of the invention as defined in the appended claims.

I claim:

1. A holder for towels and the like comprising a suction cup member having an annular mounting flange projecting from the back side thereof, said flange having an inwardly turned lip along its edge, a cup-shaped gripping member formed of soft rubber-like material and having cylindrical side walls and a flat, relatively thin outer end wall, said cylindrical side walls having an outwardly turned annular lip formed around the open end thereof, said annular lip being engageable under the lip on said mounting flange to secure said gripping member to said suction cup member, and said end wall of said gripping member being formed with slit means adapted to engage a portion of a towel or similar object to hold the same in a yieldable grip.

2. A device as defined in claim 1, wherein said suction cup member has a hole formed in the center thereof which extends almost, but not entirely, through the member, whereby a thumb tack can easily be pushed through the remaining material to secure the suction cup member to a rough or porous surface of the type unsuited to the use of the suction cup in the usual manner.

3. A holder for towels and the like comprising a wall-engaging base member having an annular

mounting flange projecting from the back side thereof, said flange having an inwardly turned lip along its edge, a cup-shaped gripping member formed of soft rubber-like material and having cylindrical side walls and a flat, relatively thin outer end wall, said cylindrical side walls having an outwardly turned annular lip formed around the open end thereof, said annular lip being engageable under the lip on said mounting flange to secure said gripping member to said base member, and said end wall of said gripping member being formed with slit means adapted to engage a portion of a towel or similar object to hold the same in a yieldable grip.
